UNITED STATES PATENT OFFICE.

HENRY BERGER, OF NEW YORK, N. Y.

DESIGN FOR CENTER-PIECE.

Specification forming part of Design No. **11,326**, dated August 12, 1879; application filed July 2, 1879.
[Term of patent 7 years.]

To all whom it may concern:

Be it known that I, HENRY BERGER, of the city, county, and State of New York, have originated a Design for Center-Piece, of which the following is a full, clear, and exact description, reference being had to the accompanying photograph, which represents a face view of my design.

My design consists in a central shield formed of a bud, a series of leaves, and an elliptical bead, which is fringed with scallops, in combination with a panel surrounding said shield, and ornamented by foliage, and with an elliptical border composed of segments, arabesques, and scrolls, whereby I obtain a design presenting a handsome and distinguishing appearance.

In the drawing, the letter A designates a bud. B are a series of leaves, and C is an elliptical bead fringed with scallops *e*, composing the central figure or shield of my design. This central shield is surrounded with a panel, F, containing foliage marked G, the same consisting of stems carrying leaves and berries.

The panel F is inclosed by an elliptical border formed of segments H, arabesques I, and scrolls J, the arabesques being arranged opposite each other, and the scrolls being situated between each of the arabesques and exterior of each of the elliptical segments.

What I claim as new, and desire to secure by Letters Patent, is—

The design for a center-piece consisting of a central shield, formed of a bud, A, a series of leaves, B, and an elliptical bead, C, fringed with scallops *e*, in combination with a panel, F, surrounding said shield, and ornamented by foliage G, and with an elliptical border composed of segments H, arabesques I, and scrolls J, substantially as shown and described.

In testimony that I claim the foregoing I have hereunto set my hand and seal this 16th day of July, 1877.

HENRY BERGER. [L. S.]
